UNITED STATES PATENT OFFICE.

ALBERTUS A. LONGMAN, OF DAYTON, OHIO, ASSIGNOR TO THOMAS J. FARRELL, OF SAME PLACE, AND WILLIAM BOTT AND JOSEPH BOTT, OF COLUMBUS, OHIO.

DESIGN FOR A GAME-TABLE TOP.

SPECIFICATION forming part of Design No. 30,468, dated April 4, 1899.

Application filed February 6, 1899. Serial No. 704,747. Term of patent 14 years.

To all whom it may concern:

Be it known that I, ALBERTUS A. LONGMAN, a citizen of the United States, residing at Dayton, in the county of Montgomery and State of Ohio, have invented and produced a new and original Design for a Game-Table Top, of which the following is a specification, reference being had to the accompanying drawings, forming part thereof, and in which like characters refer to correspondingly-formed parts.

My invention relates to a design for a game-table top for pleasure and amusement game-tables, and is fully illustrated in the accompanying drawings, in which—

Figure 1 is a top plan view of a game-table embodying my invention. Fig. 2 is a central vertical sectional elevation thereof on line X X of Fig. 1, and Fig. 3 is an enlarged similar view thereof on line Y Y of Fig. 1.

In said drawings, 10 represents the game-table top, provided on its opposite long edges with vertical straight walls 11 and 12 and on its opposite short edges, respectively, with a semicircular vertical wall 13, and a substantially straight vertical wall 14, provided on its inner edge with a series of semicircular vertical recesses 15. Adjacent said walls 11 and 12 and parallel therewith are vertical walls 17 and 18, extending from opposite

ends of said wall 14 substantially to and at a slight distance from the points of beginning of said walls 13, at which points said walls 17 and 18 terminate in points 19, as shown. Upon the inner edges of the walls 11 12 13 and the recesses 15 and the opposite sides of the walls 17 and 18 and near the top thereof are projections 20 of a uniform height from the table-top, substantially as shown.

The essential feature of my design consists of a game-table top provided on one surface with straight side flanges and parallel flanges adjacent thereto, a curved end flange joining one end of said side flange and an edge flange joining the opposite ends of said side and parallel flanges and provided with curved recesses, the edges of a series of said flanges being provided with lateral projections of substantially a uniform height from the top 50 surface of the game-table top.

What I claim is—

The design for a game-table top, substantially as shown and described.

In witness whereof I have hereunto set my hand this 18th day of January, 1899.

ALBERTUS A. LONGMAN.
